United States Patent Office

Des. 178,768
Patented Sept. 18, 1956

178,768

CAN OPENER

George A. Delf, St. Louis, Mo., assignor to Atlas Tool &
Mfg. Co., St. Louis, Mo., a corporation of Missouri

Application March 26, 1956, Serial No. 40,792

Term of patent 14 years

(Cl. D44—29)

FIG. 1.

FIG. 2.

FIG. 3.

FIG. 4.

Fig. 1 is a top plan view of a can opener embodying my new design;

Fig. 2 is a side elevational view thereof;

Fig. 3 is a front elevational view thereof, and

Fig. 4 is a perspective view showing the can opener in open condition.

I claim:

The ornamental design for a can opener, substantially as shown.
